CONTROLLING APPARATUS FOR HIGHWAY
CROSSING SIGNALSGeorge R. Pflasterer, Swissvale, Pa., assignor to
The Union Switch & Signal Company, Swiss-
vale, Pa., a corporation of Pennsylvania

Application October 30, 1936, Serial No. 108,430

12 Claims. (Cl. 246—130)

My invention relates to controlling apparatus for highway crossing signals, that is, to apparatus for the control of signals which are placed at the intersections of railways and highways for the purpose of warning users of the highway when a train is approaching.

One object of my invention is the provision of means for causing the signal to give the warning until the rear end of a train has completely cleared the highway.

The apparatus set forth in the present application is somewhat similar to that set forth in the prior copending application, Serial No. 66,255, filed February 28, 1936, for Railway track circuit apparatus, by Robert M. Gilson, and the said copending application contains claims which cover broadly certain features of the invention described in the present application.

I will describe one form of apparatus embodying my invention, and will then point out the novel features thereof in claims.

The accompanying drawing is a diagrammatic view illustrating one form of apparatus embodying my invention.

Referring to the drawing, the reference characters 4 and 5 designate the rails of a stretch of railway track over which traffic moves in both directions. The rails of the stretch are divided by insulated joints 6 into two relatively long end sections 1T and 3T which are separated from each other by a relatively short intermediate section 2T. The section 2T includes an intersection by a highway H. The intersection is protected by a signal S of any suitable type such, for example, as a bell or a light signal or a combination of both. For controlling the signal, an interlocking relay K is provided having a magnet M1 and a magnet M3. For controlling the interlocking relay magnets M1 and M3, a series track circuit including the rails of the stretch is provided.

As here shown, this track circuit includes track relays 1TR and 3TR connected across the rails at the extreme ends of the stretch, track relay 2TR connected across insulated joint 6 at the left of the intersection, and a track battery 7 connected across the insulated joint 6 at the right of the intersection. It will be apparent that relays 1TR, 2TR and 3TR will become released whenever sections 1T, 2T and 3T, respectively, are occupied by a train.

Magnet M1 is provided with a circuit which includes front contact 8 of relay 1TR and front contact 9 of relay 2TR, and magnet M3 is provided with a circuit which includes front con-

tact 10 of relay 3TR and front contact 11 of relay 2TR. That is, magnet M1 will become released whenever either relay 1TR or 2TR is released, and magnet M3 will become released whenever either relay 3TR or 2TR is released. 5

Assuming that an eastbound train, that is, a train traveling from left to right, enters section 1T to release relay 1TR, it will be clear that the opening of front contact 8 of relay 1TR will cause magnet M1 to become released so that 10 back contact 12 of magnet M1 will become closed to cause operation of signal S. When the train occupies section 2T, the releasing of relay 2TR will, of course, cause magnet M1 to remain released so that the signal will continue to operate 15 as long as section 2T is occupied. When the train enters section 3T, the interlocking feature of the relay K will prevent the closing of back contact 13 of magnet M3 so that the signal cannot operate after the train vacates section 2T and magnet 20 M1 again becomes energized to open contact 12.

The signal S is also provided with an operating circuit which includes back contact 14 of relay 2TR so that the signal S will be certain to operate as long as any portion of a train occupies the 25 intersection regardless of the condition of the interlocking relay K.

The operation of the apparatus for a westbound train has not been described because it will be understood that such operation will be 30 similar to that just described for an eastbound train.

Although I have herein shown and described only one form of apparatus embodying my invention, it is understood that various changes and 35 modifications may be made therein within the scope of the appended claims without departing from the spirit and scope of my invention.

Having thus described my invention, what I claim is:

1. In combination, a stretch of railway track insulated at each extreme end from the adjoining track and including an intersection with a highway, an insulated joint in one rail of said stretch adjacent one side of said intersection 45 and another insulated joint in the other rail of said stretch adjacent the other side of said intersection, a source of energy connected across said one insulated joint, three track relays one connected across the rails at each extreme end 50 of said stretch and one connected across said other insulated joint, and a highway crossing signal at said intersection controlled by said three relays.

2. In combination, a stretch of railway track 55

insulated at each extreme end from the adjoining track and including an intersection with a highway, an insulated joint in one rail of said stretch adjacent one side of said intersection and another insulated joint in the other rail of said stretch adjacent the other side of said intersection, a source of energy connected across said one insulated joint, three track relays one connected across the rails at each extreme end of said stretch and one connected across said other insulated joint, directional means controlled by said three relays, and a highway crossing signal at said intersection controlled by said means.

3. In combination, a stretch of railway track insulated at each extreme end from the adjoining track and including an intersection with a highway, an insulated joint in one rail of said stretch adjacent one side of said intersection and another insulated joint in the other rail of said stretch adjacent the other side of said intersection, a source of energy connected across said one insulated joint, three track relays one connected across the rails at each extreme end of said stretch and one connected across said other insulated joint, an interlocking relay controlled by said three relays, and a highway crossing signal at said intersection controlled by said interlocking relay.

4. In combination, a stretch of railway track insulated at each extreme end from the adjoining track and including an intersection with a highway, an insulated joint in one rail of said stretch adjacent one side of said intersection and another insulated joint in the other rail of said stretch adjacent the other side of said intersection, a source of energy connected across said one insulated joint, three track relays one connected across the rails at each extreme end of said stretch and one connected across said other insulated joint, a highway crossing signal at said intersection, an interlocking relay including a first magnet and a second magnet for governing said signal, a circuit for said first magnet including a front contact of the track relay connected across the rails at one end of the stretch as well as a front contact of the track relay connected across said insulated joint, and a circuit for said second magnet including a front contact of the track relay connected across the rail at the other end of the stretch as well as a front contact of the track relay connected across said insulated joint.

5. In combination, a stretch of railway track insulated at each extreme end from the adjoining track and including an intersection with a highway, an insulated joint in one rail of said stretch adjacent one side of said intersection and another insulated joint in the other rail of said stretch adjacent the other side of said intersection, a source of energy connected across said one insulated joint, three track relays one connected across the rails at each extreme end of said stretch and one connected across said other insulated joint, an interlocking relay governed by said three relays, a highway crossing signal at said intersection, and circuits for said signal governed by said interlocking relay as well as by a back contact of the track relay connected across said other insulated joint.

6. In combination, a stretch of railway track including an intersection with a highway, means including one insulated joint in one rail adjacent one side of said intersection and another insulated joint in the other rail adjacent the other side of said intersection whereby said stretch is

divided into two end sections and an intermediate section; a series track circuit including a track battery connected across said one insulated joint, a track relay connected across the other insulated joint and two other track relays, one connected across the rails at each extreme end of said stretch; a highway crossing signal at said intersection, and means governed by said three track relays for governing said signal whereby the signal will be caused to operate only when a train is approaching the intersection in the two end sections but will be caused to operate for a train moving in either direction in the intermediate section.

7. In combination, a stretch of railway track including an intersection with a highway; a track circuit for said stretch including two relays, one connected across the rails at opposite ends of the stretch, and including a source of energy connected in series with one rail as well as another track relay connected in series with the other rail, said source of energy and said other track relay being located on opposite sides of said intersection, and means governed by said three relays for governing a highway crossing signal at said intersection.

8. In combination, a stretch of railway track including an intersection with a highway, a track circuit including two track relays one connected across the rails at each end of said stretch, a source of track circuit energy connected in series with one rail of said stretch adjacent one side of said intersection, a highway crossing signal at said intersection, directional means governed by said two track relays for controlling said signal, and other means connected in series with the other rail adjacent the other side of said intersection for also controlling said signal.

9. In combination, a stretch of railway track including an intersection with a highway, a track circuit including two track relays one connected across the rails at each end of said stretch, a source of track circuit energy connected in series with one rail of said stretch adjacent one side of said intersection, a highway crossing signal at said intersection, directional means governed by said two track relays for controlling said signal, another track relay connected in series with the other rail of said stretch adjacent the other side of said intersection, and means governed by said other track relay for controlling said signal.

10. In combination, a stretch of railway track including an intersection with a highway, a track circuit including two track relays one connected across the rails at each end of said stretch, a source of track circuit energy connected in series with one rail of said stretch adjacent one side of said intersection, a highway crossing signal at said intersection, directional means controlled by said two track relays for causing said signal to operate when a train is approaching said intersection, and other means connected in series with the other rail adjacent the other side of said intersection for causing said signal to operate when a train is occupying the intersection.

11. In combination, a stretch of railway track including an intersection with a highway, an insulated joint adjacent one side of said intersection separating one rail into a first rail section and a second rail section, another insulated joint adjacent the other side of said section separating the other rail into a third rail section and a fourth rail section, a series track circuit including a source of energy and said four rail sections connected in series, a highway crossing signal at

said intersection, and means governed by said series track circuit for governing said signal.

12. In combination, a stretch of railway track including an intersection with a highway, an insulated joint adjacent one side of said intersection separating one rail into a first rail section and a second rail section, another insulated joint adjacent the other side of said section separating

the other rail into a third rail section and a fourth rail section, a series track circuit including a source of energy and said four rail sections connected in series, a highway crossing signal at said intersection, and means including an interlocking relay governed by said series track circuit for controlling said signal. 5
